UNITED STATES PATENT OFFICE.

CLARENCE M. KNAPP, OF CICERO, INDIANA.

RAIL ANCHOR.

Application filed May 17, 1926. Serial No. 109,682.

The present invention relates to improvements in rail anchors or anti-creepers, and the primary object of the invention is to provide a device of this character adapted for positioning upon the base flange of railroad rails and engageable with an object, preferably the sleeper or cross tie for the rails, in a manner for preventing creeping of the rails longitudinally in the direction of traffic.

10 A further object of the invention is to provide an improved type of rail anchor being of a resilient nature and adapted for clamping engagement with the rail base and engageable with the cross tie in a manner whereby tendency of the rail to creep longitudinally will increase the biting action of the anchor upon the rail.

15 A further object of the invention is to provide a rail anchor embodying a pair of terminally disposed jaw portions for biting engagement with the upper face and side edges of the rail base in a manner whereby the anchor will not be affected by the vibration of traffic moving along the rails, and which 20 anchor is also of a nature to permit of its being elongated for ready applying of the anchor to the under side of the rail base.

25 Other objects and advantages of the invention will be apparent during the course of 30 the following detailed description, taken in connection with the accompanying drawing forming a part of this specification and in which drawing:

35 Figure 1 is a top plan view of a portion of a railroad rail and tie therefore, and showing the improved anchor in position.

Figure 2 is a bottom plan view of the rail and showing the anchor applied thereto and engaging the tie for the rail.

40 Figure 3 is a section on line 3—3 of Figure 1 and looking in the direction of the arrows.

Figure 4 is a fragmentary side elevation of the rail and showing the anchor in end 45 elevation as applied to the rail.

Figure 5 is a plan view of a sheet or bar of steel and showing the anchors laid out in blank form for stamping.

Figure 6 is a view on a reduced scale, 50 taken substantially on line 6—6 of Figure 3, and showing the manner in which certain portions of the jaws of the anchor will be caused to bite into the rail upon tendency of the rail to move in the direction of the 55 arrow.

Referring to the drawing in detail, and

wherein similar reference characters designate corresponding parts throughout the several views, the letter A designates a railroad rail of ordinary construction, B a supporting tie for the rail A, and C the improved anchor for preventing creeping of the rail A longitudinally, or transversely of the tie B.

The rail A embodies the usual base flange 65 10 adapted to rest upon the upper surface of the tie B, and be secured to the tie as by the usual spikes or fastening elements 11 engaging the opposite edges of the flange.

The anchor C which is formed from the 70 blanks 12 cut or stamped preferably from a flat bar of steel, is preferably bent into the formation shown, and then treated or tempered for rendering the anchor of a resilient nature. This resiliency of the anchor 75 serves for permitting applying of the device to the rail base, and after application of the anchor, serves for retaining the anchor in proper position upon the rail.

The blanks 12 are bowed transversely at 80 their medial lines for forming a bearing loop 13 provided with an arcuate bearing face 14 adapted to engage one longitudinal side face 15 of the tie B. The arms 16 of the bearing loop 13 extend rearwardly in 85 converging relation and terminate in outwardly or oppositely bent spring loops 17. Extending from the outer end of the spring loops, are forwardly diverging arms 18 the forward ends of which terminate in a plane 90 rearwardly of the bearing face 14 as is clearly illustrated in Figures 1 and 2. These arms 18, which may be termed clamping arms, are provided at their forward or outer ends with jaws 20 which are adapted for 95 biting engagement, at an angle, with the opposite edges of the base flange 10. These jaws 20 which extend upwardly from the major upper surface 21 of the anchor, are adapted to overlie the edge portions of the 100 base flange at an angle to the longitudinal center of the rail in a manner for retaining the anchor upon the flange, and which overlying portion by reason of its contact with the upper inclined surface of the base flange, also serves as a further gripping portion for the jaws. As will be observed in Figure 4, the major upper surface 21 of the anchor 105 engages throughout the bottom face of the base flange 10 and by reason of the jaws 20 engaging the base flange at an angle as 110 clearly shown in Figure 1, the anchor is

held against possible tilting when in position upon the base flange.

In applying the device to the rail, one of the jaws 20 is first positioned about one edge of the base flange, and then by lengthening of the anchor due to the yielding of the spring loops 17 and bearing loop 13, the companion jaw may be hooked about the opposite edge of the base flange. Due to the spring tension of the anchor, the jaws 20 will be drawn into tight frictional engagement with the opposite edges of the base flange, as will be readily apparent. The anchor may then be readily slid longitudinally of the base flange for bringing the bearing face 14 into bearing engagement with the side face 15 of the tie B. As will be observed in Figure 2, this sliding of the anchor toward the tie B may be readily accomplished since no material biting action will be had by the jaws 20 when moving along the side edges of the base flange in a direction toward the tie. It may here again be mentioned that when the bearing face 14 engages the tie B, the forward ends of the clamping arms 18 are spaced from the tie.

Normally, the distance between the jaws 20 is less than the width of the base flange 10, and after the anchor is applied to the base flange the spring tension of the anchor holds the jaws tightly in place against the longitudinal edges of the base flange. The inward pressure of the jaws 20, due to the spring tension, securely holds the anchor in place even though no strain of creepage is being exerted against the bearing loop 13 by the rail A. As a pressure is applied to the bearing loop 13, owing to a tendency of the rail A to move in a direction of the arrow X in Figure 6, this pressure of the arcuate bearing face 14 against the side face 15 of the tie B, causes the loop 13 to be expanded and the free ends of the arms 16 to spread slightly from one another which in turn swings the free ends of the forwardly diverging clamping arms 18 toward one another in a manner for causing the gripping edges 25 of the jaws 20 to grip more firmly the side edges of the base flange 10. This inward swinging of the free ends of the clamping arms 18 is made possible by the normal tendency of the jaws 20 to swing toward one another into biting engagement with the edges of the base flange 10. This biting action of the jaws 20 with the side edges of the base flange 10 upon tendency of the rail to shift longitudinally, is clearly illustrated in Figure 6. As will also be apparent in Figure 6, by so having the clamping arms 18 extending in diverging relation toward the tie B, that movement of the rail A in the direction of the arrow X will cause the sharp gripping edges 25 to bite into the side edges of the base flange 10.

When the anchor is in service, it will

readily be apparent that tendency of the rail to creep in the direction of the traffic will be effectively checked by reason of the biting action of the jaws 20 caused by engagement of the bearing loop 13 with the cross tie 70 for the rail.

From the foregoing description it will be apparent that a novel and efficient type of resilient rail anchor has been provided which may be economically manufactured, which is capable of ready attachment to the base flange of railroad rails, and which when in service will effectively check tendency of the rail to creep in the direction of travel upon the rails.

Changes in detail may be made in the specific form of the invention herein shown and described, without departing from the spirit of the invention or the scope of the following claims.

I claim:

1. A rail anchor comprising an intermediate bearing loop for engagement with one side of a tie for the rail, and resilient clamping arms arranged at each side of the bearing loop for biting engagement with the base flange of the rail.

2. A rail anchor comprising an intermediate bearing loop for engagement with one side face of a tie for the rail, and resilient clamping arms arranged at each side of the bearing loop and extending in forwardly diverging relation for biting engagement at their outer ends with the opposite edges of the base flange of the rail.

3. A resilient rail anchor comprising an intermediate bearing loop for engagement with one side face of a tie for the rail, and clamping arms arranged at each side of the bearing loop and each having a jaw formed at its outer end for biting engagement with the side edges of the base flange of the rail.

4. A rail anchor comprising an intermediate bearing loop for engagement with one side face of a tie for the rail, and clamping arms yieldably connected with the rear portion of the bearing loop and extending forwardly in diverging relation at each side of the loop for engagement with the side edges of the base flange of the rail rearwardly of the engaging portion of the bearing loop with the side face of the tie.

5. A resilient rail anchor comprising an intermediate loop portion provided with an arcuate bearing face, and resilient clamping arms extending from the rear of the loop portion at each side of the loop, and extending in forwardly diverging relation to the longitudinal center line of the rail.

6. A resilient rail anchor comprising an intermediate loop portion provided with a forwardly disposed arcuate bearing face and rearwardly converging arms, and clamping arms yieldably connected at the rear portions of said loop arms and extending for-

wardly and outwardly of their respective loop arms and terminating in a plane rearwardly of the bearing face of said loop portion.

5 7. A resilient rail anchor comprising an intermediate bearing loop, and clamping arms extending at an angle from each side of the bearing loop and having gripping edges normally spaced a distance less than 10 the width of the base flange of a rail to which the anchor is to be applied.

8. A resilient rail anchor comprising an intermediate bearing loop for engagement with one side face of a tie for the rail, resilient clamping arms arranged at each side 15 of the bearing loop, and jaws formed at the outer end of each clamping arm and having portions overlying the upper surface of the base flange of the rail and extending at an 20 angle to the length of the rail.

9. A resilient rail anchor comprising an intermediate bearing loop having an arcuate bearing face at its forward end and having oppositely bent spring loops at its 25 rear end, and clamping arms extending forwardly and at an angle from each of the spring loops and having jaws formed at

their outer ends disposed in a plane between the bearing face and spring loops of the bearing loop.

10. A rail anchor formed of a single strip of metal bent centrally of its ends for forming a loop portion provided with a forward arcuate bearing face and rearwardly converging arms, oppositely bent loops at the rear ends of the arms, and clamping arms extending forwardly in diverging relation from the oppositely bent loops and having jaws formed at their outer ends provided with gripping edges disposed rearwardly of the plane of the arcuate bearing face.

11. A resilient rail anchor comprising an intermediate spring bearing loop having a bearing face for engagement with one face of a tie for the rail at the longitudinal center of the rail, and clamping arms integrally and yieldably connected with the spring bearing loop and having jaws engaging the opposite longitudinal edges of the base flange of the rail whereby upon tendency of the rail to creep in a direction toward the tie, the jaws will be drawn into further biting engagement with the edges of the base flange.

CLARENCE M. KNAPP.
